Primary Examiner — Kendra Leslie Hamilton*Assistant Examiner* — Amanda Christensen(74) *Attorney, Agent, or Firm* — Wolf, Greenfield & Sacks, P.C.(57) **CLAIM**

The ornamental design for a car-mounted wireless charger, as shown and described.

DESCRIPTION

FIG. 1 is a front view of a car-mounted wireless charger showing my new design;

FIG. 2 is a right side elevation view thereof;

FIG. 3 is a left side elevation view thereof;

FIG. 4 is a rear elevation view thereof;

FIG. 5 is a top plan view thereof;

FIG. 6 is a bottom plan view thereof;

FIG. 7 is a top, front, left side perspective view thereof; and, FIG. 8 is a top, rear, right side perspective view thereof.

The broken lines depict portions of the car-mounted wireless charger that form no part of the claimed design.
